TOBACCO PIPE

Olaf M. Ingebretsen, Prospect Park, Pa.

Application February 11, 1947, Serial No. 727,866

4 Claims. (Cl. 131—213)

1.

This invention has general reference to tobacco pipes and relates to the species or form thereof designed to afford a sanitary smoke. More specifically, my invention has for its primary object to provide a novel form of tobacco pipe containing provisions which positively prevent the passage of nicotine or other noxious residuum from the tobacco bowl being drawn through the mouthpiece or bit into the smoker's mouth.

Another object is to provide a tobacco pipe embodying a baffle or dam, intermediate the suction passage from the pipe bowl and the mouthpiece duct, which is so located relative to a drain-off or moisture diverting and collecting passage, that it is normally impossible for any nicotine, saliva, or other residuum, developed incidental to smoking from entering the mouthpiece duct and the smokers' mouth.

A further object of this invention is to provide a tobacco pipe of the species or form indicated embodying provisions whereby normally free communication between the pipe bowl passage, as well as the moisture collecting passage, and the mouthpiece is maintained, irrespective of whether or not the pipe stem and said mouthpiece be directly aligned or relatively disaligned.

With the above-stated objects and ancillary advantages in view, my invention essentially consists in certain novel features and details of construction, and arrangement of parts, as herein-after fully disclosed, illustrated by the accompanying sheet of drawings, and more particularly recited in the concluding claims.

In the drawings:

Fig. 1 is a vertical longitudinal section through a partially-curved, or downwardly-inclined, stem style of tobacco pipe.

Fig. 2 is an end elevation of the same as viewed looking from the right-hand towards the left hand of Fig. 1.

Figs. 3-7 inclusive are cross-sections through the mouthpiece and pipe stem, respectively taken on the planes designated by the angled-arrows III—III, IV—IV, V—V, VI—VI and VII—VII appearing in Fig. 1, and drawn to larger scale for clearer illustration of the details.

Fig. 8 is a sectional view, similar to Fig. 1, illustrating the adaptations of my invention to a straight-stem pipe; and

Fig. 9 is a fragmentary sectional view illustrating the application of my improvements to tobacco pipes having a mouthpiece frictionally connected to the pipe stem.

In describing the forms of my invention shown by the accompanying sheet of drawings specific

terms will be employed for purposes of clarity, but it is to be understood that such terms are used in a descriptive sense and not for purposes of limitation. Each specific term is intended to include all technical equivalents which serve in a similar manner to accomplish an analogous purpose.

Referring more in detail to the drawings, the tobacco pipes illustrated each comprises the usual bowl 10, stem 11, and unitary mouthpiece 12. The stem 11 includes two spacedly and distinctive passages or parallel bores 13, 14, the former 13 of which connects from the bowl 10 to the mouthpiece 12, and the latter 14 from said mouthpiece to the lower end of the bowl at 15, where it is fitted with a removable screw-plug 16, serviceable normally to seal or close in the outlet end of said bore 14. In accordance with my invention the respective ends of the bores 13, 14 where they connect into the mouthpiece 12 are flaringly shaped; that is to say the end of the bore 13 is formed with eccentrically related upper and lower curvilinear tapers 17, 18, preferably of differential, or lesser and greater radius respectively, said tapers meeting one another on a line diametrically through the axis of the bore 13, as best understood from Fig. 5. At this juncture, it is to be noted that the bores 13, 14 are preferably of smaller and greater diameter respectively, and that the tapers 17, 18 at the outer end of the bore 14 are approximately of corresponding radius.

Turning now to the unitary mouthpiece 12, which in Figs. 1 and 9 is depicted as applied to the stem of the bent type, and in Fig. 8 to a straight stem pipe. More specifically referring to Figs. 1 and 9 it is to be observed the mouthpiece 12 is formed of hard rubber, or other desirable material, and that it is provided with a small laterally expanded smoke duct 19, preferably as shown having its outer and wider end or slot portion 20 tangentially related to that of the moisture drain off passage 14 in the stem 11, see Fig. 4 to best advantage. Otherwise expressed, the outer upper edge portion of the smoke-duct slot 20 is aligned with the top curvature of the passage 14, in order that a small riser 21 intervenes the confronting mouthpiece slotted end portion 20, whereby any moisture from the smoker's mouth draining over the said riser portion 21 is prevented from being drawn back into the mouth. In addition the mouthpiece 12 is provided with communicating relatively fork-borings 22, 23 the former 22 whereof is preferably inclined at an angle of approximately thirty degrees in respect to the longitudinal axis of the passage 14; where-

as the latter 23 parallels the corresponding axis of the bore 13, with provision of an intervening inclined dam 24. The bore 23 is provided with a tapering, preferably, segmental-shaped cut-out 25, see Fig. 4 to best advantage, functional to retard the passage of any tobacco residuum being drawn over the dam 24 into the inclined bore 22 as readily appreciable by steady smokers, or those conversant with the art of sanitary pipe making. It will be also clearly understood that the inclined bore 22, when drilled from the outside-in, will have its outer end closed in by a suitable plug or set-screw 26.

In Figs. 1 and 8 I have shown the mouthpiece 12 as attached to the stem 11 by means of a screw-threaded connection 27 which normally ensures said mouthpiece and stem being retained in alignment with unimpeded communication between the respective bores 13, 14 and duct 19. On the other hand when the pipe stem 11 is reduced at 28, as shown in Fig. 9, for friction engagement in the socket end 29 of the mouthpiece should, or when, said parts become relatively disaligned, it is to be particularly remarked that by providing the upper tapers 17, 18 and confronting undercut 25, as well as the lower tapers 17, 18 and confronting slot 20, free flow communication is always maintained between the stem suction or smoke bore 13 and mouthpiece bore 23, as well as between said mouthpiece inclined bore 22 and the drain-off bore 14.

From the foregoing it will be readily understood that the improved pipe of this invention conduces to a perfectly dry smoke, inasmuch as the passage of any nicotine or other residuum from the bowl 10 by way of the suction bore 13 is firstly checked from entering the mouthpiece bore 23 by the undercut 25, while any accumulation collecting thereat that may be drawn over the top of the inclined dam 24 will creep down the underside of said dam, and be deflected by the adjoining curvilinear taper 17 into the drain-off passage 14, such action being materially aided by the saliva from the smoker's mouth passing down the smoke duct 19, in an obvious manner.

In conclusion, while I have shown and described, with some particularity, preferred embodiments of the invention it will be realized that the details may be changed to adapt the improvements to other forms of smoker's pipe than the species illustrated; hence the right is reserved to make such changes, or modifications, as may fairly come within the scope of the subject-matter hereafter claimed.

Having thus described my invention, I claim:

1. In a tobacco pipe comprising a bowl and stem unit having connectable bores in said stem,

one of which serves as the smoke-conduit from the bowl and the other as a collector-drain-off passage; the combination of a unitary mouthpiece embodying communicating bores defining an intervening dam, one of said bores leading from the smoke-conduit and the other connecting therewith into the collector drain-off passage; means jointly defining a trap for residuum drawn from the tobacco bowl at the juncture between the stem and mouthpiece; and means defining a riser between the collector-drain-off passage and the mouthpiece smoke-duct whereby nicotine, saliva and other residuum, accumulating in said drain-off passage is positively prevented from entering the smoker's mouth.

2. A tobacco pipe comprising a bowl and stem unit; spaced longitudinal bores in the stem, one of which serves as the smoke-conduit and the other as a collector-drain-off passage, and both of said bores have the mouthpiece adjoining ends divergently-flared; a mouthpiece attached to the stem outer end and embodying angularly-related communicating bores defining an intervening inclined dam, one of said bores leading from the smoke conduit and the other connecting therewith into the smoke-duct of the mouthpiece; taper means defining a residue trap at the juncture between one of the mouthpiece bores and the stem smoke-conduit; and a riser at the juncture between the other mouthpiece bore and the collector-drain-off passage.

3. A tobacco pipe in accordance with claim 2 wherein the stem bores are spaced in parallel; wherein the flared ends of said bores are defined by upper and lower eccentrically-related curvilinear tapers of differential radii, for the purpose specified.

4. A tobacco pipe in accordance with claim 2 wherein the mouthpiece communicating bores include an angle of approximately thirty-degrees; wherein the bore connecting from the stem smoke-conduit is provided in its lower portion with a segmental-shaped tapering cut-out; and wherein the mouthpiece smoke-duct outer end is laterally expanded to define a segmental riser in confronting relation to the opposing flared end of the drain-off passage, for the purpose specified.
